ABSTRACT

An improved method and apparatus for severing weft yarns in a fabric woven from glass or carbon yarns on a loom in which the weft is inserted by a water jet an airjet or other shuttleless device in which the weft yarn is presented to a continuously rotating abrasive disc during beat up to sever the yarn.

**MEANS FOR SEVERING OF WEFT YARN DURING
WEAVING**

This invention relates to an improved method for the severing of weft yarns in a fabric woven from glass or carbon yarns.

The object of the invention is an improved method for the severing of the weft threads of woven fabric during the weaving operation, and more particularly to fabrics constructed from easily abraded fibers such as glass or carbon, and further with particular reference to fabrics woven on a water-jet or similar high speed loom.

The method according to the invention comprises mounting a continuously rotating abrasive disc adjacent to the selvedge of a fabric being woven to abrade the weft yarn during beat up and means for controlling the yarn relatively to the disc.

The invention will be described with reference to the accompanying drawings:

FIG. 1 is a plan view of part of one side of a loom reed and sley with the severing disc for the weft in position;

FIG. 2 is a similar plan view of the opposite side of the loom.

FIG. 3 is a side elevation of the severing disc shown in FIG. 1 looking in the direction of the arrow A in FIG. 1;

FIG. 4 is a side elevation of the severing disc shown in FIG. 2 looking in the direction of the arrow B in FIG. 2.

The method is carried out on a loom of normal construction with a slay carrying a reed and healds through which warp yarns 11 pass and which form the shed.

An abrasive disc 1 driven by an electric motor 2 is mounted on the loom frame in close proximity to the selvedge of the fabric 3 being woven, with the axis of the disc parallel to that of the weft 4.

The weft 4 may be propelled through the shed of a water-jet loom by a water jet 5 in which discrete quanta of water are used to propel the weft yarn; or the weft may be inserted by air jets or by other shuttle-less devices.

A pair of serrated weft guide plates 6 are mounted in the end of a reed 7. In operation the weft is inserted through the shed and clamped by a clamp 7¹ behind the jet orifice. As the reed begins to beat up, the weft 4 located in serrations 6¹ of the plates 6 passes over and is tensioned between the plates 6 and as the reed advances the weft between the plates is presented to the disc 1 and is severed.

A second abrasive disc 8 driven by a motor 9 is mounted on the opposite side of the loom frame in

close proximity to the opposite side of the loom frame in close proximity to the opposite selvedge again with the axis of the disc parallel to that of the weft.

As the weft yarn 4 completes its traverse through the shed of the warp yarns 11 and reaches this side of the loom, it is caught between three threads warp yarns 12 which are continuously twisted together by a separate mechanism of known construction. The weft before being twisted up with the warp yarns 12 passes over two fixed weft guide plates 13 on the loom frame between which the disc 8 rotates.

The warp yarns 12 retain the tension on the weft yarns 4 which after being caught up with the warp yarns are severed by the disc 8 and the severed ends are taken away with the warp yarns 12.

As the position of the healds changes at the end of the sequence of operations in which the weft yarn 4 is inserted, the weft yarn is held between the warp threads 11 and the selvedge is tensioned by the continued twisting of the aforementioned three catching warp yarns 12.

By this means, the weft yarn 4 is pulled firmly against the abrasive cutting disc 8 on the right hand side of the loom. The two guide plates 13 prevent the weft yarn from moving tangentially with respect to the disc 8.

The abrasive wheels 1, 8 are required to run continuously during weaving operation at a high surface speed.

The foregoing parts are mounted as a standard loom frame (not shown).

What I claim is:

1. Apparatus for severing weft yarn in a loom having a sley and a reed comprising a continuously rotating disc mounted at one side of the loom adjacent the fabric being woven, a pair of plates mounted on one end of the reed and over which the weft is adapted to extend, said disc being disposed to rotate between said plates and said plates having serrations to locate the yarn thereon, means for applying tension to the weft extending over the plates and means for bringing the weft after each pick into contact with the disc to sever the web.

2. Apparatus for severing weft yarn as in claim 1 comprising a second continuously rotating disc similarly mounted at the opposite side of the loom, a second pair of serrated plates mounted on the loom between which the second disc rotates, means for applying tension to the weft yarn extending over said plates and means for bringing a weft yarn at beat up into contact with the second disc to sever the yarn.

3. Apparatus as in claim 1 and an electric motor for continuously driving the rotating disc.
